CROSS THREAD LAYING MECHANISM

John P. Weis and Albert H. Weis, Nyack, N. Y., assignors to Metropolitan Sewing Machine Corporation, Nyack, N. Y., a corporation of Delaware

Application October 16, 1930, Serial No. 489,048

15 Claims. (Cl. 112—100)

This invention relates to sewing machines and more particularly to an improved cross stitch laying mechanism therefor, by means of which ornamental stitching on the top surface of the 5 work is obtained, and which improvement is applicable to different kinds of sewing machines, such as long and short arm, and also to cylinder sewing machines manufactured by the well-known Metropolitan Sewing Machine Corpora- 10 tion.

The primary object of the invention is the provision of a cross thread laying mechanism, by means of which perfect stitching of delicate threads, yarns, rayon, floss or silk of different 15 sizes and with several threads is obtained when the machine is running at speed, especially when a heavy covering is desired with a long stitch, thereby insuring rapid production.

A further object of the invention is the provision of a cross thread laying mechanism, simple in construction and accurately operative and which will lay the thread or threads close to and directly on the material being stitched, requiring no thread take-up and which will work with two 25 or more needles of either wide or narrow gauge or spacing, which is not possible with other similar devices now in use, and which obviates the necessity of a movable thread guide since the cross thread in the present improvement is conducted 30 directly from the supply to a tension and thence to a stationary guide where the cross thread carrier or hook picks up and drops the thread loops in the path of the needles, by means of which the thread is stitched to the top of the work. 35 As the present improvement, simple in construction, efficient in use and inexpensive to manufacture, is applicable as stated, to various kinds of sewing machines, only a brief description of such machines is deemed necessary herein to 40 make clear the construction and operation of the present improvement, since it is applicable to any multiple needle sewing machine.

In the drawings accompanying and forming a 45 part of this specification, Figure 1 is an end view of a top and bottom rotary shaft Metropolitan sewing machine having this improved cross stitch laying mechanism applied thereto.

Figure 2 is a top view of the cross stitch laying mechanism, the top of the sewing machine being 50 illustrated in dotted lines.

Figure 3 is a side view of the mechanism shown in Figure 2.

Figure 4 is a perspective view illustrating in 55 dotted lines a Metropolitan cylinder sewing ma-

chine having this improved cross stitch laying mechanism applied thereto.

Figure 5 illustrates a part of the thread carrier. Figure 6 illustrates the thread carrier lever mounted on the presser bar.

Figure 7 illustrates partly in section, the assemblage of driving crank and crank shaft and one of its bearings.

Figure 8 illustrates a cross stitch made with a two-needle machine having one looper, the 65 looper thread producing an ornamental stitch on the bottom of the work also.

Figure 9 illustrates a cross stitch made with a two-needle machine having two loopers with two rows of stitches on the bottom of the work 70 and the cross stitch on top thereof.

Figure 10 illustrates this improved cross stitch laying mechanism applied to a short arm, flat bed sewing machine, the cross stitch laying mechanism being shown in full lines and the sewing 75 machine illustrated in dotted lines.

Similar characters of reference indicate corresponding parts in the several views.

Before explaining in detail the present improvement and mode of operation thereof, we 80 desire to have it understood that the invention is not limited to the details of construction and arrangement of parts which are illustrated in the accompanying drawings, since the invention is capable of other embodiments, and that the 85 phraseology which we employ is for the purpose of description and not of limitation.

In the machine illustrated in Figures 1 to 3, 5, 6 and 7, the base 1 has the usual trunk 2, top arm 3 and head 4, in which is located the 90 needle bar 5 and presser foot bar 6. The machine has feeding mechanism 7 and looper mechanism 8 operated by a bottom rotary shaft 9 connected by connecting rods, not shown, with the top rotary shaft 10 for transmitting motion to the 95 latter for operating the needle bar 5 and cross stitch laying mechanism.

The presser bar 6 has the usual presser foot 11 to co-operate with the feed dog 12 for feeding the work, and the needle bar has needles 13 co- 100 acting with loopers 14 for making the stitches 15 (Figure 9). Operating across and in front of the needles is a thread carrying hook 17 for laying the cross stitch 16 (Figure 9). This hook has a rounded free end 18 (see Figure 5) provided with a downwardly slanting, backwardly extending thread engaging loop forming hook 19 located at the under side of the end of this member and in position to pass over and pick up the cross thread 20 at 21, (Figure 2) where 110

this cross thread extends from the stationary guide 22 directly to the stitches being made at the presser foot opening 23. This guide 22 is stationary with relation to the presser foot or presser foot bar, but being carried thereby, it of course moves up and down therewith during the feeding movement thereof to accommodate different thicknesses of goods.

The cross thread loops are cast on the work 24 10 instantly as the hook reverses its motion when the needle threads 25 tightly draw down on the work to secure these cross threads in place.

The thread carrier 17 has a shank 26 clamped at 27 to the arm 28 of an oscillating right angle 15 or bell crank lever 29 moving freely on the presser bar 6 (see Figures 1 to 6), and which bar is provided with a groove 30 for the reception of the end 31 of a screw 32 having a lock nut 33, whereby the screw is maintained in place 20 for controlling the lever 29. The arm 34 of the lever 29 receives a screw ball stud 35 (see Figure 1) for one end of a connector 36, the opposite end of which, 38, is connected by a screw ball stud 37 with the thread carrier operating means. 25 By this means, the thread carrier can oscillate on the bar 6 and move up and down therewith.

The thread laying mechanism shown in Figure 4 is similar to that just described in connection with Figure 1.

30 This cross stitch laying means is operated from the needle drive shaft 10, (shown as a top rotary shaft in Figures 1, 2 and 3, and as a transverse rotary shaft in Figure 4) by a crank 39 (Figures 2, 3 and 4) and connection 40, the opposite end 35 of which (Figures 1, 2 and 3) is coupled as at 41 to the free end 42 of a lever 43 secured at 44 to a shaft 45, which may be of solid form, as shown in Figures 2 and 3. In Figure 4, the connector 40 attached to the crank 39 of the 40 transverse shaft 10 is, in turn, connected as at 41 to the end 42 of a lever 43 attached as at 44 to a tubular shaft 45.

This shaft 45, in Figures 1 and 2, operates in supporting bearings 46 and 47, while in Figure 45 4, this shaft 45 is tubular and is supported by the needle operating shaft 48 which rocks in bearings 49 and 50 and is operated from the transverse shaft 10 by a connection 51 and crank arm 52 connected to the needle operating shaft 50 48, the opposite end of which is coupled by a lever 53 to the needle bar 5.

Secured to the shaft 45 (Figures 1 to 4) as at 54 is an arm 55 carrying at its lower end the screw ball stud 37 hereinbefore referred to, and 55 by means of this driving mechanism from the top rotary shaft 10 (Figures 1 to 3) or the transverse rotary shaft 10 (Figure 4), the cross stitch laying means is operated and which is applicable to different types of machines with little, if any, 60 change in the parts thereof, by merely selecting the necessary connections, levers, shafts and bearings whereby the improvement may be used with a variety of machines now in use and thus easily converted in an economical manner and 65 without the return of the machines to the manufacturer.

This improved mechanism being easy to adjust and thread, does not easily get out of repair and will stitch accurately at high speed even 70 when making stitches at twenty-five to thirty per inch, which is due to the inverted hook of the thread carrier.

In Figure 8, at 15a, a twin needle stitch made with a thread carrying looper coating with a 75 pair of needles is shown and, in Figures 1 to 3,

the improvement is applied to a Metropolitan long arm, flat bed rotary top and bottom shaft machine while, in Figure 4, the improvement is applied to a Metropolitan cylinder machine and, in Figure 10, it is applied to a Metropolitan short arm needle lever type flat bed machine, in which it will be seen that movement for the cross stitch laying finger 17 is obtained from the shaft 9 having a gear 56 in mesh with another gear 57 secured to a shaft 58 mounted in suitable bearings of the trunk 80 2 of the machine frame, a collar 59 on this shaft 58 preventing end play of the shaft.

The gear 57 is provided with a hole located off center in which the ball stud 60 is secured and coupled to a bearing 61 of a rod 62 which, in turn, 85 is coupled as at 63 to a ball stud 64 carried by an arm 65 of a rocker lever or tubular shaft 66 pivoted at 67 on the needle lever stud 68, the nut 69 of which limits end movement of the lever on the stud. The upright or vertical arm 70 of the lever 66 carries a ball stud 71 connected as at 73 to a rod 72 which, in turn, is connected as at 74 to a ball stud 75 of a lever 76 secured at 77 to a bar 78 having means for guiding the presser bar 6 and preventing it from turning in its bearings, and 90 for which purpose, the presser bar 6 has clamped thereto a collar 78' having a stem 79 terminating in a yoked bearing 80 carrying the guide bar 78 which is thus permitted to rock in this yoked bearing while having an up and down movement with 95 the presser bar 6.

The lower end of this bar 78 is clamped as at 81 to a yoked lever 82 having a segmental gear 83 in mesh with a similar gear 84 of the lever 29 for giving movement to the finger 17. The usual 110 presser spring 85 with its end 86 resting on the stem 79 gives pressure to the presser foot in the usual way, and the usual presser foot lifting means is provided, not shown.

Thus, this mechanism just described constitutes 115 the means for operating the cross stitch laying finger 17. It will be observed that in all forms, the operating means for the oscillating cross finger or thread carrier, includes a vertically supported member connected to the thread carrier or finger 120 by a single connection, thus very much simplifying the connection between the cross finger and its operating means and permitting motion to be directly transmitted to the oscillating finger or thread carrier, thereby doing away with various 125 linkage, joints or pivots which would cause excessive overthrow as the speed of the machine varies from minimum to maximum each time the machine is started. It requires almost micrometer precision to lay a stitch accurately as is now demanded especially as the machine is operated at a speed of 3,000 R. P. M. or over, and any variation either from underthrow or overthrow of the parts during the operation of the machine, which would be the result of multiple linkage, would cause a 130 variation of the stitch formation. Moreover, the necessity for repairs is not only diminished but a 135 number of parts eliminated by this single connection.

It is to be understood that by describing in detail herein any particular form, structure or arrangement, it is not intended to limit the invention beyond the terms of the several claims or the requirements of the prior art.

Having thus explained the nature of our said 140 invention and described a way of constructing and using the same, although without attempting to set forth all of the forms in which it may be made, or all of the modes of its use, we claim:

1. In a sewing machine having a presser foot 145

- bar, the combination of stitching mechanism including a plurality of needles and cross stitch laying mechanism operative to form and lay loops of a cross thread directly on the material being 5 stitched without the use of a thread take-up or movable thread guide and comprising a shiftable thread carrier having its axis of movement coinciding with the axis of the presser foot bar, and means for operating it and including a vertically supported member and a single connecting member between said shiftable thread carrier and said vertically supported member in combination with a guide stationary relative to said presser foot bar but movable therewith for the thread leading 10 80
- 15 from the thread supply, said guide being so located that the thread carrier will pick up and drop the thread loops in the path of the needles, whereby the cross loops are stitched to the top of the work. 20 85
- 20 2. In a sewing machine having a presser foot bar, the combination of stitching mechanism including a plurality of needles and cross stitch laying mechanism operative to form and lay loops of a cross thread directly on the material being 25 90
- 25 stitched without the use of a thread take-up or movable thread guide and comprising a shiftable thread carrier pivotally mounted on the presser foot bar, and means for operating it and including a vertically supported member and a single 30 95
- 30 connecting member between said shiftable thread carrier and said vertically supported member in combination with a guide stationary relative to said presser foot bar but movable therewith for the thread leading from the thread supply, said 35 100
- 35 guide being so located that the thread carrier will pick up and drop the thread loops in the path of the needles, whereby the cross loops are stitched to the top of the work. 40 105
- 40 3. In a sewing machine, the combination of stitching mechanism including a plurality of needles and cross stitch laying mechanism operative to form and lay loops of a cross thread directly on the material being stitched without the use of a thread take-up or movable thread guide 45 110
- 45 and comprising a shiftable thread carrier and means for operating it in combination with a stationary guide for the thread leading from the thread supply, said guide being so located that the thread carrier will pick up and drop the thread 50 115
- 50 loops in the path of the needles, whereby the cross loops are stitched to the top of the work, said thread carrier comprising a member having an inverted hook having a rounded free end and a downwardly extending backwardly slanting 55 120
- 55 loop forming hook. 60 125
- 60 4. In a sewing machine, the combination of stitching mechanism including a plurality of needles and cross stitch laying mechanism operative to form and lay loops of a cross thread directly on the material being stitched without the use of a thread take-up or movable thread guide 65 130
- 65 and comprising a shiftable thread carrier and means for operating it in combination with a stationary guide for the thread leading from the thread supply, said guide being so located that the thread carrier will pick up and drop the thread loops in the path of the needles, whereby the cross loops are stitched to the top of the work, said sewing machine having a presser foot and 70 135
- 70 its bar and said thread carrier being supported for oscillating movement on said bar and said stationary thread guide being supported by said presser foot. 75 140
- 75 5. In a sewing machine having stitch forming mechanism including needle mechanism and a 80 145
- presser foot and its bar, of an oscillating thread carrier carried by the presser foot bar for laying a cross stitch and having its axis of movement coinciding with the axis of the bar, means for operating said thread carrier, and a stationary thread guide carried by the presser foot and so located in position that the thread carrier will engage the thread between it and the stitch mechanism. 85
6. In a sewing machine, the combination of stitching mechanism including needle mechanism, a presser foot and its bar, an oscillating thread carrier, a thread guide stationary relative to said presser foot bar but movable therewith located in position whereby the thread carrier will pass over and pick up the thread where it extends from said guide to the stitch forming means, and means for oscillating said thread carrier and including means connected to the main driving shaft of the machine comprising a lever system including a rock shaft, crank mechanism, gear mechanism, a vertically supported member connected with the rock shaft and a single connecting member between said oscillating thread carrier and said vertically supported member. 90
7. In a sewing machine, the combination of stitching mechanism including needle mechanism, an oscillating thread carrier, a stationary thread guide located in position whereby the thread carrier will pass over and pick up the thread where it extends from said guide to the stitch forming means, and means for oscillating said thread carrier and including means connected to the main driving shaft of the machine comprising a lever system including a rock shaft, crank mechanism and gear mechanism, said cross thread carrier having an inverted hook at its end. 105
8. In a sewing machine, the combination of stitching mechanism including needle mechanism, an oscillating thread carrier, a stationary thread guide located in position whereby the thread carrier will pass over and pick up the thread where it extends from said guide to the stitch forming means, and means for oscillating said thread carrier and including means connected to the main driving shaft of the machine comprising a lever system including a rock shaft, crank mechanism and gear mechanism, said cross thread carrier having an inverted hook at its end formed by a downwardly extending backwardly slanting hook forming portion. 110
9. In a sewing machine having needle mechanism and presser foot mechanism, and means for operating the needle mechanism, said presser foot mechanism including a presser foot constructed for the passage of the needles therethrough, an oscillating thread carrier located above the presser foot and having an inverted hook formed end, means for oscillating said thread carrier, a stationary thread guide located adjacent to the presser foot for guiding the thread to the needle opening in the presser foot whereby the thread carrier is in position to pass over the thread and engage said thread, the thread carrier and stationary guide being located adjacent to the presser foot and one carried thereby. 130
10. In a sewing machine having needle mechanism and a presser foot and its bar, and means for operating the needle mechanism, an oscillating thread carrier located above the presser foot and having an inverted hook formed end, means for oscillating said thread carrier, a stationary thread guide located adjacent to the presser foot 135
- 140
- 145
- 150

for guiding the thread to the needle opening in the presser foot whereby the thread carrier is in position to pass over the thread and engage said thread, the thread carrier and stationary guide being located adjacent to the presser foot, one carried thereby and the other by the presser foot bar.

11. In a sewing machine, the combination of stitching mechanism including a plurality of needles and means for operating them, presser foot mechanism including a presser foot and a supporting bar therefor, a stationary guide carried by the presser foot, a cross thread carrier supported for oscillating movement by the presser foot bar and having an inverted hook at its end, and means for oscillating said carrier on the bar whereby it is operative in position to pass over the thread guided by the stationary guide and lay the thread in loops on the work to be stitched down by the needles.

12. In a sewing machine having an overhanging arm, the combination of stitching mechanism including needle mechanism and a needle operating shaft located in the overhanging arm, a presser foot and its bar, an oscillating thread carrier, a thread guide stationary relative to said presser foot bar but movable therewith located in position whereby the thread carrier will pass over and pick up the thread where it extends from said guide to the stitch forming means, and means connected with the needle operating shaft for oscillating said thread carrier and including a vertically supported member and a single connection between said oscillating thread carrier and the vertically supported member.

13. In a sewing machine having an overhanging arm, the combination of stitching mechanism including needle mechanism and a needle operating shaft located in the overhanging arm, a presser foot and its bar, an oscillating thread carrier, a thread guide stationary relative to said presser foot bar but movable therewith located in position whereby the thread carrier will pass over and pick up the thread where it extends from

45

said guide to the stitch forming means, and means for oscillating said thread carrier and including a lever system and a shaft extending transversely of the overhanging arm and with which said lever system is connected and also including a vertically supported member and a single connection between said oscillating thread carrier and the vertically supported member.

80

14. In a sewing machine having an overhanging arm, the combination of stitching mechanism including needle mechanism and a needle operating shaft located in the overhanging arm, a presser foot and its bar, an oscillating thread carrier, a thread guide stationary relative to said presser foot bar but movable therewith located in position whereby the thread carrier will pass over and pick up the thread where it extends from said guide to the stitch forming means, and means for oscillating said thread carrier and comprising a lever system, a rock shaft connected therewith and with the needle operating shaft and including a vertically supported member and a single connection between said oscillating thread carrier and the vertically supported member.

85

15. In a sewing machine, the combination of a presser foot bar, stitching mechanism, a single oscillatory thread carrier, a thread guide co-operating therewith and located in position whereby the thread carrier will pass over and pick up the thread where it extends from said guide to the stitch forming means, means for oscillating said thread carrier and comprising a rock shaft, and means connected with the rock shaft for operating it and including a vertically supported member and a single connecting member between said shiftable thread carrier and said vertically supported member, the thread carrier having its pivotal axis coincident with that of the presser foot bar and the thread guide being stationary relative to the thread carrier but movable with the presser foot bar.
